US0D1063438S

(12) **United States Design Patent** (10) **Patent No.:** **US D1,063,438 S**
(45) **Date of Patent:** **** Feb. 25, 2025**

(54) **PAPER TOWEL RACK**

(71) Applicant: **NINGBO CHSIRGA METAL PRODUCTS CO., LTD.**, Yuyao (CN)

(72) Inventor: **Chen-Yu Lien**, Yilan (CN)

(73) Assignee: **NINGBO CHSIRGA METAL PRODUCTS CO., LTD.**, Yuyao (CN)

(**) Term: **15 Years**

(21) Appl. No.: **29/948,571**

(22) Filed: **Jun. 21, 2024**

(30) **Foreign Application Priority Data**

May 21, 2024 (CN) 202430302144.7

(51) **LOC (15) Cl.** **06-06**

(52) **U.S. Cl.**
USPC **D6/518**

(57) **CLAIM**

The ornamental design for a paper towel rack, as shown and described.

DESCRIPTION

FIG. 1 is a first perspective view of a paper towel rack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the using state of the paper towel rack thereof; and, FIG. 10 is an exploded view of the using state of the paper towel rack thereof.

The broken lines in the figures are for the purpose of illustrating portions of the paper towel rack and form no part of the claimed design. Additional broken lines in the figures showing the paper towel roll illustrate environment and form no part of the claimed design.

1 Claim, 10 Drawing Sheets
